DESIGN FOR A BILLFOLD

William St. Thomas, Gloversville, N. Y., assignor
to E. J. Wilkins Co., Gloversville, N. Y.

Application July 21, 1937, Serial No. 70,567

Term of patent 3½ years

To all whom it may concern:

Be it known that I, William St. Thomas, a citizen of the United States of America, residing at Gloversville, in the county of Fulton and State of New York, have invented a new, original, and ornamental Design for a Billfold, of which the following is a specification, reference being had to the accompanying drawing, forming part thereof.

The figure is an elevational view of a billfold,

showing my new design, the side opposite to that shown in the drawing being plain and formed of the same grain leather as shown by the end portions in the drawing. The shiny portions shown in the drawing are intended to represent patent leather.

I claim:—

The ornamental design for a billfold as shown and described.

WILLIAM ST. THOMAS.
